UMBRELLA TABLE OR SIMILAR ARTICLE

Berry C. Collins, Tallahassee, Fla.

Application April 29, 1955, Serial No. 35,739

Term of patent 14 years

(Cl. D33—14)

FIG. 1.

FIG. 2.

Figure 1 is a perspective view of an umbrella table or similar article showing my new design; and

I claim:

The ornamental design for an umbrella table or similar article, as shown.
